Specification for Design.

Patented May 2, 1916.

Application filed April 20, 1914. Serial No. 833,310. Term of patent 7 years.

To all whom it may concern:

Be it known that I, ELMO Q. WILSON, a citizen of the United States, residing in the city and county of San Francisco, State of California, (whose post-office address is 2215 Bush street,) have invented a new, original, and ornamental Design for an Automobile-Body, of which the following is a specification, reference being had to the accompanying drawings, forming part thereof, in which—

Figure 1, is a side elevation of an automobile following the lines of my ornamental design. Fig. 2, is a plan view from above

of the same. Fig. 3, is a front elevation of the same.

My design relates more particularly to the body portion of automobiles.

I claim:

The ornamental design for an automobile body as shown.

In testimony whereof, I have hereunto set my hand this thirteenth day of April 1914.

ELMO Q. WILSON.
